UNITED STATES PATENT OFFICE.

OTTO A. HOKANSON, OF WOODSTOCK, ILLINOIS, ASSIGNOR TO WOODSTOCK TYPEWRITER COMPANY, OF WOODSTOCK, ILLINOIS, A CORPORATION OF ILLINOIS.

TYPEWRITER.

Application filed February 11, 1925. Serial No. 8,351.

This invention relates to typewriter mechanism in which provision is made for operating a type bar without actuating the escapement mechanism for shifting the carriage, and has for its object the provision of such mechanism which will be simple and efficient in construction and operation, and which shall permit of the operation of accent keys without shifting the platen.

10 The invention is exemplified in the combination and arrangement of parts shown in the accompanying drawings and described in the following specification, and it is more particularly pointed out in the appended claims.

In the drawings—

Fig. 1 is a fragmentary elevation, with parts in section, showing one embodiment of the present invention; and

20 Fig. 2 is a fragmentary rear elevation of the parts shown in Fig. 1.

The numeral 10 designates the rack for controlling the transverse movement of the platen carriage, the rack being in mesh with a pinion 11 carried on a shaft 12 provided with an escapement wheel 13. A dog rocker 14 is pivotally mounted at 15 and is provided with dogs 16 and 17 for controlling the movement of the escapement wheel 13. A spring not shown normally draws the upper portion of the dog rocker 14 forwardly, the amount of oscillation of the dog rocker being controlled by stop screws 19 and 20 which engage fixed stops, not shown. An adjustable contact screw 21 is carried in the dog rocker 14 above the pivotal axis thereof and in position to register with a contact member in the form of an arm 22 on a bell crank lever pivoted at 23 on a bracket 24. The bracket 24 carries a stop 24' for limiting the movement of the contact member 22 to a position in registration with the screw 21. The contact member 22 carries an ear 22' for engaging the stop 24'. The stop 24' also forms a backing member for transmitting the force of the universal bar frame to the contact member 22. The bracket 24 is secured by fasteners 25 to a bar 26 forming a part of the universal bar frame for the typewriter. The bar 26 is provided with forwardly extending arms 27 which are connected with an arcuate universal bar 28 positioned in the path of the type bars 29. The bar 26

is provided with spaced downwardly extending arms 30 which are pivoted at 31 to downwardly extending legs 32 on a hanger yoke 33. The yoke 33 is supported on pivot screws 34 connected with the machine frame.

The lever 22 is provided with a laterally extending arm 35 having a finger 36 at its outer end which extends through an opening in an arm 37 of a bell crank lever pivoted at 38 on the arm 30 of the universal bar frame. The lever 37 is provided with a downwardly extending arm 39, the lower end of which is provided with a contact surface 40 in position to engage a lug 41 on an arm 42 carried by a sleeve 43 mounted to oscillate upon a shaft 44. The shaft 44 is journaled in posts 45 which project upwardly from the base of the typewriter frame. A crank arm 46 is secured to the sleeve 43 and is provided with a laterally extending pin 47. A plurality of slotted links 48 are mounted on the pin 47 and are held in spaced relation by collars 49. Each of the links 48 is connected to a sub-lever 50 pivoted at 51 on the typewriter frame. The sub-levers 50 are actuated by key levers 52 in the usual manner. Each of the sub-levers 50 is connected with a type bar 29.

The shaft 44 is provided with a crank arm 53 connected by a link 54 to a tailpiece 55 extending downwardly from the dog rocker 14. A crank arm 56 is connected to the shaft 44 and is provided with a pivotal connection 57 to an arm 58. The arm 58 is connected with a letter space bar, not shown.

In the ordinary operation of the machine, the type bars strike the universal bar 28 at the end of the stroke and move the bar 26 rearwardly. This will cause the member 22 to engage the contact screw 21 and oscillate the dog rocker to effect a letter space movement of the platen. In many languages there are letters which require accent marks and in order that these letters may be accented when desired without the necessity of providing special type carrying the accent marks, the present invention provides for accent keys. The spacing operation for the particular letter in question is produced by the operation of the type bar carrying the letter itself so that when the accent key is struck the platen should not be shifted. These accent

keys are each actuated by a sub-lever 50 having a link 48 connected with the pin 47. The links 48 are provided with slots, as shown in Fig. 1, which permit the type bars to travel freely during the first part of their movement, but prior to the engagement of the type bars with the universal bar 28, the end of the slot in the link 48 will engage the pin 47 and partially rotate the sleeve 43 in a counter-clockwise direction, as viewed in Fig. 1. Since the arm 42 is connected with the sleeve 43 this will raise the arm 42 to contact with the face 40 on the lever arm 39. This will rotate the lever arm against the tension of a spring 59 swinging the arm 37 downwardly and lifting the arm 22 from in front of the contact screw 21. This will permit the movement of the bar 26 rearwardly without affecting the dog rocker and consequently the platen remains stationary. As many accented type bars 29 may be provided as desired. The key levers for actuating these type bars are commonly designed "dead keys" or "silent keys". Since the sleeve 43 is loosely journaled on the shaft 44, the shaft 44 is free to oscillate when the space bar is operated and this oscillation will move the link 54 to shift the dog rocker and effect letter space movement of the platen carriage.

I claim:

1. In a typewriter, the combination with an escapement wheel, of a dog rocker for controlling said escapement wheel, a universal member having a stop thereon for actuating said dog rocker, a lever pivoted on said universal member and having one arm thereof movable into and out of position between said stop and dog rocker, a type bar, and connecting means between said type bar and lever for shifting said lever when said type bar is operated.
2. In a typewriter, the combination with an escapement wheel, of a dog rocker for controlling said escapement wheel, a universal bar frame for actuating said dog rocker, a bracket mounted on said universal bar frame having a stop positioned in alignment with said dog rocker, a bell crank lever

pivoted on said bracket and having one arm 50 thereof movable into and out of registration with said stop to render said stop effective for actuating said dog rocker, a second bell crank lever pivoted on said universal bar frame for actuating said first-named bell 55 crank lever, an oscillating member for actuating said second named bell crank lever, a type bar, and means having a lost motion connection between said type bar and oscillating member to effect movement of said oscillating member and said bell crank levers during the latter part of movement of said type bar.

3. In a typewriter, the combination with escapement mechanism, of a universal member 65 for actuating said escapement mechanism, a rock shaft, letter space mechanism connected with said rock shaft for actuating said escapement mechanism to produce letter space movement, a sleeve journaled on 70 said rock shaft, type bars for actuating said universal member, means operated by said sleeve for rendering said universal member inoperative to effect actuation of said escapement mechanism, and means actuated in 75 unison with one of said type bars for effecting operation of said sleeve when said type bar is operated.

4. In a typewriter, the combination with escapement mechanism, of a dog rocker for 80 controlling said mechanism, a rock shaft for moving said dog rocker, a universal member for moving said dog rocker, letter space mechanism for operating said rock shaft, 85 type bars for operating said universal member, a sleeve journaled on said rock shaft, means connected with said sleeve for rendering said universal member inoperative to oscillate said dog rocker, and means selectively connecting said sleeve with a number 90 of special ones of said type bars to cause said sleeve to be oscillated thus rendering said dog rocker inoperative when said special type bars are operated.

In testimony whereof I have signed my 95 name to this specification on this 5th day of February A. D. 1925.

OTTO A. HOKANSON.
